T. N. TOLLEFSON

POCKET ATTACHMENT

Filed March 11, 1924

Fig. 2.

T. N. Tollefson,
Inventor

By *Oliver A. Brown*
Attorney

UNITED STATES PATENT OFFICE.

TALMER N. TOLLEFSON, OF SIOUX FALLS, SOUTH DAKOTA, ASSIGNOR OF ONE-TENTH
TO S. W. LARSON, OF BRANDON, SOUTH DAKOTA, AND NINE-TENTHS TO ANNA M.
TOLLEFSON, OF SIOUX FALLS, SOUTH DAKOTA.

POCKET ATTACHMENT.

Application filed March 11, 1924. Serial No. 698,480.

To all whom it may concern:

Be it known that I, TALMER N. TOLLEFSON, a citizen of the United States, residing at Sioux Falls, in the county of Minnehaha 5 and State of South Dakota, have invented certain new and useful Improvements in Pocket Attachments, of which the following is a specification.

This invention relates to new and useful 10 improvements in attachments for pockets of overalls, or the like, and has for its principal object to provide a means whereby various kinds of tools, such as pliers, carpenter rules, or the like, may be held in the pocket 15 against accidental loss or displacement when the person wearing the garment is in a stooping, crouching, or sitting position.

Another important object of the invention 20 is to provide a garment attachment of the above mentioned character, wherein elastic means is provided, for forming a restricted opening, for seating and supporting the tool inserted in the pocket against accidental displacement therefrom, and yet permits the ready removal of the tool whenever 25 necessary.

A further object of the invention is to provide a device of the abovementioned 30 character, which is simple in construction, inexpensive, strong and durable, and further well adapted for the purposes for which it is designated.

Other objects and advantages of this invention will become apparent during the 35 course of the following description.

In the accompanying drawing, forming a part of this specification, and in which like numerals designate corresponding parts throughout the same:

40 Figure 1 is an enlarged front elevation of a pocket, parts broken away, showing my attachment in position therein, and

Figure 2 is a transverse section, taken on the line 2—2 of Figure 1.

45 In the drawing, wherein for the purpose of illustration is shown the preferred embodiment of my invention, the numeral 1 designates a portion of the garment, upon which is adapted to be stitched or sewed the 50 pocket forming flap 2. Suitable stitching, such as is shown at 3 in the drawing, extends around the marginal edges of the flap 2, on the sides and bottom thereof for stitching the same to the garment, whereby a

pocket is formed for the reception of tools 55 of various kinds, such as pliers, rules, and the like, as are used by carpenters. Ordinarily, with the pockets now provided on the overalls or garments worn by the workman, there is a tendency of the tool within the 60 pocket to drop out therefrom, where the workman is in stooping or crouching position. To overcome accidental loss of the tool from within the pockets in which they are placed, I provide an attachment there- 65 in, which will be hereinafter more fully described.

My attachment comprises an elastic strip 70 of material 4, formed preferably of rubber, and this strip is secured, at its outermost side edges, by the stitching 3, to the sides of the flap 2, and portion of the garment, to which the flap is stitched. The elastic strip 4 is stitched along the upper longitudinal edge to the inner side of the flap 2, and this 75 stitching, which is shown at 5 in the drawing, extends for the major intermediate portion of the strip, and terminates at its respective ends, at a point adjacent the sides of the flap, in a manner as clearly shown 80 in Figure 1 of the drawing. Suitable stitching 6 extends from the upper central portion of the elastic strip 4 to the bottom portion thereof, in a manner as also clearly shown 85 in the drawings.

The elastic strip 4 is further stitched along 90 its sides to the garment 1, and this stitching, which is shown, at 7 and 8 in the drawings, extends from the outer ends of the stitching 5, on the upper portion of the elastic strip, and converges from the central bottom portion of the elastic strip, in the manner as clearly shown in Figure 1 of the drawing. In this manner, a restricted opening 9 is provided between intermediate portions of the elastic strip 4 and the garment 1, for the reception of the tool to be supported 95 in the pocket.

By providing an elastic strip, in the manner as above described, when a pair of pliers or the like is inserted between the flap 2 and the garment 1, the head of the plier will 100 be caused to pass between the elastic strip 4, and the adjacent portion of the garment, as the opening formed by the elastic strip 105 measures smaller toward the bottom thereof, the head of the pliers or the like being securely grasped by the elastic webbing and

held in the pocket against accidental displacement, regardless of the position of the person wearing the garments.

While I have shown the preferred embodiment of my invention, it is to be understood that various changes in the size, shape, and arrangement of parts, may be resorted to, without departing from the spirit of the invention, and the scope of the appended 10 claims.

Having thus described my invention, what I claim is:

1. In a garment, a pocket forming flap 15 stitched thereto along the outer edges of the side and bottom thereof, an elastic strip stitched at its ends to the inner sides of the flap, at the point where said flap is stitched to the garment, said elastic strip stitched along its upper longitudinal edge to said 20 flap, the strip being further stitched adjacent the sides thereof to the garment forming an article receiving and holding means between the strip and the garment.

2. In a garment, a pocket forming flap 25 stitched thereto along the outer edges of the sides and bottom thereof, and elastic strips stitched at its side edges to the inner side of said flap, at the point where said flap is stitched to said garment, said elastic strip

being stitched along its upper longitudinal 30 edge to said flap for the major intermediate portion thereof, the elastic strip being further stitched adjacent the side thereof to the garment, said last mentioned stitching converging from the upper portion of 35 said strip toward the central bottom thereof, to provide a restricted opening between the garment and the strip.

3. In a garment, a pocket forming flap 40 stitched thereto along the outer edges of the sides and bottom thereof, an elastic strip stitched at its side edges to the inner side of said flap, at the point where the flap is stitched to said garment, said elastic strip being stitched along its upper longitudinal 45 edge to said flap for the major intermediate portion thereof, the elastic strip being further stitched adjacent the side thereof to the garment, said last mentioned stitching converging from the upper portion of said strip 50 toward the central bottom thereof, to provide a restricted opening between the garment and the strip, said strip having a row of stitching on the central portion of the flap and extending from the upper edge 55 thereof to the lower edge of the same.

In testimony whereof I affix my signature.
TALMER N. TOLLEFSON.
